UNITED STATES PATENT OFFICE.

CHRIST JAMES CHAMALES, OF CHICAGO, ILLINOIS.

RAILROAD SIGNALING DEVICE.

1,354,954.

Specification of Letters Patent.

Patented Oct. 5, 1920.

Application filed January 19, 1920. Serial No. 352,401.

To all whom it may concern:

Be it known that I, CHRIST JAMES CHAMALES, a citizen of the United States, and a resident of the city of Chicago, in the county of Cook and State of Illinois, have invented a new and useful Improvement in Railroad Signaling Devices, of which the following is a full, clear, and exact description.

10 My invention relates to improvements in railroad signaling devices, and it consists in the combinations, constructions and arrangements herein described and claimed.

An object of my invention is to provide a 15 railroad signaling device which will indicate to the engineer of a train his location, as, for instance, where a train is approaching a bend in the track which should be taken at a low speed, by operating an audible signal in the cab of the engine.

A further object of my invention is to provide a signaling device which is simple in construction, positive in operation, and not liable to easily get out of order.

25 A further object of my invention is to provide a signaling device which is actuated by auxiliary track devices which operate inductively and which are not subject to the difficulties that attend signaling 30 devices that are operated by making electrical contacts with track devices.

A further object of my invention is to provide a signaling device, by means of which an engineer may positively know 35 that he is on the right track, even though he may be unable to see the track, as, for instance, in a blinding snow storm.

Other objects and advantages will appear 40 in the following specification, and the novel features of the invention will be particularly pointed out in the appended claims.

45 My invention is illustrated in the accompanying drawings, forming part of this application, in which

Figure 1 is a sectional view of a portion of a car or cab of an engine, with my improved invention applied thereto,

Fig. 2 is a front view of a track,

Fig. 3 is a plan view of a contact lever,

Fig. 4 is a plan view of a portion of a track, equipped with auxiliary devices,

Fig. 5 is a plan view of a pair of tracks, showing the use of the signaling device,

Fig. 6 is a view of a modified form of track equipment, and

Fig. 7 is a sectional view of a car, show-

ing the contact lever and magnets disposed on the bottom thereof.

In carrying out my invention, I provide on the under side of a cab or car 1 a bracket 2 having a pivot rod or fulcrum 3, upon which is mounted a contact lever 4. The latter is provided with a counterweight 5 at one end, and at the opposite end bears an electro-magnet 6 which is connected by 65 means of conductors 7 and 8 with a battery 9. The electro-magnet is designed to be energized continuously, a battery of the gravity type being preferably used.

At the opposite end of the lever 4, i. e., 70 on the same side of the counterweight 5, is an insulating bracket 10 which is provided with two contacts 11 and 12 respectively. These contacts are shown diagrammatically in Fig. 1, but are preferably spring contacts and are arranged to be bridged by the end 13 of the lever 4 which normally rests on the bracket 10, and which is insulated from the remaining portion of the lever by 75 any suitable insulation 14.

The contacts 11 and 12 are connected with a battery 15, a buzzer 16 or other audible electro-magnetical device, and this in series with the battery, as shown.

Referring now particularly to Fig. 4, I 85 have shown therein a track consisting of track rails 17 and ties 18. Disposed on the ties are auxiliary devices 19. These are preferably iron or steel rails or bars. They are located at places where they may act in 90 conjunction with the operation already described to effect the sounding of the audible signal on the car or cab.

From the foregoing description of the various parts of the device, the operation 95 thereof may be readily understood. As has been stated, the bars 19 are disposed along the track, and the engineer or conductor knows that at a given station he should receive three rings from the buzzer or audible 100 signal, while the train is passing over the track. Normally the lever 4 is in the position shown in Fig. 1, being held in this position by the weight 5, so that the spring contacts 11 and 12 are disconnected and 105 the buzzer or audible signal 16 is silent. When, however, the magnet 6 passes above one of the bars 19, it is attracted toward the bar. The magnet never touches the bar, being kept from actual contact therewith by 110 the fact that the opposite end of the lever springs upwardly, bringing the portion 13

into engagement with the spring contacts 11 and 12, so as to bridge these contacts and thus permit a flow of current through the local circuit containing the buzzer, thereby sounding the latter. When the magnet has moved past the bar 19, the counterweight 5 will raise the magnet 6 and will break the circuit of the buzzer at the contacts 11 and 12. When the next bar 19 is reached, the 10 buzzer will be again sounded. For an arrangement such as shown in Fig. 4, the buzzer will be sounded three times, and will thus indicate to the engineer or conductor the particular station or the particular place 15 on the track at which the train or engine has arrived. In the drawing, I have shown the auxiliary bars 19 as being much shorter than they would actually be in reality, this being due to the fact that the limited space 20 would not permit the correct relative showing. Also in Fig. 1, the switching apparatus is shown greatly enlarged, this being for the sake of illustration only.

In Fig. 5, I have shown a double track 25 arrangement in which the signaling device may be very effectively used. It will be noted that on the track 20 there are five auxiliary bars which I have indicated at 19^x, while on the track 21 there are three bars 30 which I have indicated at 19^y. A connecting track 22 is shown joining the two tracks 20 and 21. Assuming that at the position where the bars 19^x and 19^y are located, the engineer knows that he will get a signal 35 to indicate the proper station or place, as, for instance, five rings on track 20, and that, due to a blinding snow storm, he cannot see the track, he will be sure of being on the right track at the position when he 40 gets the five rings that he naturally expects at this point. If, however, the switch should be so placed that the train should be accidentally shunted off onto track 21, then the engineer will get three rings only, and 45 he will know at once that he is on the wrong track and may stop the train in time to prevent accident.

In Fig. 6, I have shown a modified form 50 of track arrangement, in which the bars 19^a, 19^b, and 19^c are arranged side by side, but on different parts of the track. The trains would have their signaling devices arranged correspondingly, so that a train, with its signaling devices arranged above the bars 55 19^a, would get three rings, one arranged above the bars 19^b would get four, and one arranged with the signal devices arranged above the bars 19^c would get five rings at this particular position. In this 60 case, as in the preceding case, illustrated in Fig. 5, should an engine or car get on the track where it was not designed to go, the engineer or conductor would get a signal which would indicate to him at once that 65 he was on the wrong track.

The device described above acts magnetically, and not by direct electric contact with one of the track rails or bars. It will, therefore, not be dependent upon a good electrical contact, and will be little influenced 70 by snow or ice. The device will serve as an ample warning for any engineer who passes by a visible signal, since, where the track bars are placed near visible signals, they will invariably sound the audible sig- 75 nal on the train, if the visible signal has not been seen or has been disregarded.

The use of the device to indicate the proper track is especially advantageous in those arrangements where a multiplicity of 80 tracks are encountered, as, for instance, when entering a large city. Moreover, by placing bars, such as those shown at 19, diagonally on the track, emergency signals can be made. Thus, if a bridge should be 85 down, and it is desired to signal a train moving at high speed, which will be due in half an hour or so, one has only to place the bars 19 on the track in order to give the engineer or conductor ample warning of 90 the impending danger.

While I have described in detail the construction of the device, it is obvious that other devices based on the same general plan might be made without departing from the 95 spirit or the scope of the invention.

If a stray piece of metal should be attracted by the magnet 6, the additional weight of the metal may cause the downward movement of the magnet, and the closing of the contacts 11 and 12, thereby causing the ringing of the audible signal 16. The stray piece of metal may be dropped by opening the switch 50. Then the switch is again closed, the apparatus is ready for its 105 normal operation. In order that the engineer may know that the magnet is in working order a small electric light 51 is placed in the circuit of the battery 9. As long as the light is on, the engineer knows that the 110 magnet is in good working order, and should the light go out, he would at once know that something was wrong with the circuit, and could make the necessary repairs in time to prevent accident.

It is obvious that instead of having an electro-magnet on the vehicle, the electro-magnet, together with the signaling device, might be placed on the track, and the metal bar might be carried by the train, without 120 departing from the spirit of the invention. Instead of using an audible signal, a visible signal, such as a light, or a movable indicator, might be used.

I claim:

1. The combination with a track having a magnetizable metal bar, of a railway vehicle adapted to run on the track, an electrically operated signal carried by the railway vehicle, a local circuit having a 130

- source of current for energizing the signal, a lever having a counterweight at one end, a magnet carried by the lever at the opposite end and being normally overbalanced by said counterweight, a conductor carried by the end of the lever bearing the counterweight and insulated from said counterweight, said conductor being moved to close the local circuit when the magnet is in the field of attraction of said bar, whereby the signal is operated. 25
2. The combination with a track having a magnetizable metal bar, of a railway vehicle adapted to run on the track, an electrically operated audible signal carried by the railway vehicle, a local circuit having a source of current for energizing the signal, a lever having a counterweight at one end, a magnet carried by the lever at the opposite end and being normally overbalanced by said counterweight, the end of the lever bearing the counterweight being arranged to close the local circuit when the magnet is in the field of attraction of said bar, whereby the signal is sounded. 30
3. The combination with a track having a magnetizable metal bar, of a railway vehicle adapted to run on the track, a lever carried by the vehicle, an electro-magnet mounted on one end of said lever, a source 35 of current carried by the vehicle for constantly energizing the electro-magnet, a counterweight for counterbalancing the electro-magnet, a bracket carried by the vehicle, one end of said lever being insulated from the main body portion of the lever and arranged to rest normally on said bracket, an electrically operated audible signal, a local circuit therefor, including a battery and a pair of contacts, said contacts being carried by said bracket and arranged to be bridged by the movement of the end of the lever when the electro-magnet is in the field of attraction of the bar. 40

CHRIST JAMES CHAMALES.
